CLAIM

The ornamental design for a display screen with graphical user interface for managing customized messaging, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

The FIGURE is a front view of a display screen with graphical user interface for managing customized messaging. The outer broken lines in the FIGURE are representative of a display screen.

The broken lines showing the display screen and the remainder of the graphical user interface form no part of the claimed design.
